(57) **CLAIM**

The ornamental design for a bottle with cap and box, as shown and described.

DESCRIPTION

FIG. 1 is a top perspective view of the box portion of the claimed design with the bottle and cap removed;

FIG. 2 is a top plan view thereof;
FIG. 3 is a bottom plan view thereof;
FIG. 4 is a front elevation view thereof;
FIG. 5 is a rear elevation view thereof;
FIG. 6 is a left side elevation view thereof;
FIG. 7 is a right side elevation view thereof;
FIG. 8 is a top perspective view of the cap portion of the claimed design with the bottle and box removed;
FIG. 9 is a top plan view thereof
FIG. 10 is a front elevation view thereof;
FIG. 11 is a rear elevation view thereof;
FIG. 12 is a left side elevation view thereof;
FIG. 13 is a right side elevation view thereof;
FIG. 14 is a top perspective view of the bottle and cap portions of the claimed design with the box removed;
FIG. 15 is a top plan view thereof;
FIG. 16 is a bottom plan view thereof;
FIG. 17 is a front elevation view thereof;
FIG. 18 is a rear elevation view thereof;
FIG. 19 is a left side elevation view thereof;
FIG. 20 is a right side elevation view thereof;
FIG. 21 is a top perspective view of the bottle portion of the claimed design with the cap and box removed;

FIG. 22 is a top plan view thereof;
FIG. 23 is a bottom plan view thereof;
FIG. 24 is a front elevation view thereof;
FIG. 25 is a rear elevation view thereof;
FIG. 26 is a left elevation view thereof;
FIG. 27 is a right elevation view thereof;
FIG. 28 is a top perspective view of a bottle with cap and box showing our new design;
FIG. 29 is a top plan view thereof
FIG. 30 is a bottom plan view thereof;
FIG. 31 is a front elevation view thereof;
FIG. 32 is a rear elevation view thereof;
FIG. 33 is a left side elevation view thereof;
FIG. 34 is a right side
FIG. 35 is a top perspective view of the bottle with cap and box of FIG. 28 with the top portion of the box removed;
FIG. 36 is a top plan view thereof;
FIG. 37 is a bottom plan view thereof;
FIG. 38 is a front elevation view thereof;
FIG. 39 is a rear elevation view thereof;
FIG. 40 is a left side elevation view thereof; and,
FIG. 41 is a right side elevation view thereof.
